UNITED STATES PATENT OFFICE

158,447

BOBBY PIN OPENER AND HOLDER

Jack L. Day, Oakland, Calif.

Application August 8, 1949, Serial No. 4,355

Term of patent 14 years

(Cl. D86—10)

To all whom it may concern:

Be it known that I, Jack L. Day, a citizen of the United States, residing at Oakland, in the county of Alameda and State of California, have invented a new, original, and ornamental Design for a Bobby Pin Opener and Holder, of which the following is a specification, reference being had to the accompanying drawing, forming part thereof.

Fig. 1 is a perspective view of a bobby pin holder and opener, showing my new design;
Fig. 2 is a front elevational view;
Fig. 3 is a plan elevational view;
Fig. 4 is a rear elevational view, and
Fig. 5 is a side elevational view thereof.

I claim:

The ornamental design for a bobby pin holder and opener, substantially as shown.

JACK L. DAY.
